SNOW BALL DISPENSING CABINET

Kurt A. Rose, Meridian, Miss.

Application December 13, 1956, Serial No. 44,179

Term of patent 14 years

(Cl. D2—3)

Fig. 1 is a rear perspective view of a snow ball dispensing cabinet, showing my new design, the other side being substantially like the side shown.

Fig. 2 is a front perspective view thereof.

What I claim is:

The ornamental design for a snow ball dispensing cabinet, as shown and described.
